[57] CLAIM

The ornamental design for a key bow cover, as shown and described.

DESCRIPTION

FIG. 1 is a rear elevational view of a key bow cover showing my new design;

FIG. 2 is a left side elevational view thereof, the right side being a mirror image;

FIG. 3 is a front elevational view thereof;

FIG. 4 is a top plan view thereof;

FIG. 5 is a bottom plan view thereof;

FIG. 6 is a partial, enlarged vertical cross-sectional view thereof, taken in the direction of line 6—6 of FIG. 2; and,

FIG. 7 is a top left side perspective view thereof, the broken-line showing of the key being for illustrative purposes only and forming no part of the claimed design.

FIG. 1.

FIG. 2.

FIG. 3.

FIG. 4.

FIG. 5.

FIG. 6.

FIG. 7.
